CLAIM

The ornamental design for a plug device for swimming pool fence system, as shown and described.

DESCRIPTION

FIG. 1 is a side view of a plug device for swimming pool fence system in a fence post opening in a pool deck;

FIG. 2 is a side view thereof;

FIG. 3 is a top view thereof;

FIG. 4 is a bottom view thereof;

FIG. 5 is a perspective view thereof; and,

FIG. 6 is an exploded perspective view thereof.

The broken lines shown in FIGS. 1-2 and FIGS. 5-6 illustrate surface indicia of the plug device for swimming pool fence system that form no part of the claimed design. The additional broken lines shown in FIG. 1 illustrate environment and form no part of the claimed design.

1 Claim, 6 Drawing Sheets
